UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

METALLIC WALL PLATE

Application filed September 24, 1928. Serial No. 308,103.

The invention relates to railway freight train cars and more particularly to metallic wall plates therefor having an integral strut-beam adjacent one or both side margins of a metallic plate, and the object of the invention is to reinforce such a strut-beam adjacent its middle portion which is its place of maximum bending moment under columnar or beam stresses.

Such a construction when used in house or roofed cars (such as box, automobile, stock, etc.,) would eliminate the use of corner post or door post, or if the strut-beam is positioned horizontally, would eliminate the use of the end plate or end sill. When used in open top cars (gondolas) the corner post could be dispensed with.

Another object of the invention is to form a wall of a railway car of two plates secured together along a horizontal line and to form an integral post adjacent each vertical margin thereof and to reinforce the connection between the two plates at each corner post.

In the drawings:

Fig. 1 shows a railway box car equipped with a typical application of my device.

Fig. 2 is a side elevation of Fig. 1.

Fig. 3 is a section on line 3—3 of Fig. 1.

Fig. 4 is a perspective view of a metallic plate having an integral corner post formed therein and reinforced according to my invention.

Fig. 5 is a modification of Fig. 4.

Fig. 6 shows the plate of Fig. 5 without the reinforcement.

Figs. 1 to 4 inclusive show my invention applied to a railway box car wherein the metallic plate 1 forming the end wall of the car is provided with an integral Z shape member adjacent each of its opposite vertical margins, which members are secured to the upper side plates 2 and lower side sills 3, respectively, on each side of the car, thus forming the usual corner post, that is, the integral Z shape formation or members performs the functions of the usual corner post of the car. (This construction is disclosed and claimed in my co-pending application Serial No. 308,102, filed September 24, 1928.)

Each Z shape member comprises a web 4, an outer flange 5 and an inner flange 6. Such a Z shape construction provides a very strong column to resist stresses longitudinally of its length, and furthermore, such a Z-shape construction forms a very efficient beam to resist stresses normal to its length. This statement is true whether the stresses are parallel to the web, normal to the web or diagonal thereto, therefore, such a Z shape formation forms a very efficient corner post construction.

When a member is subjected to columnar stresses or beam stresses, the maximum fibre stress occurs adjacent the middle of the member, and as a corner post (or in fact any post in a railway car) is subjected to both of such stresses, I prefer to reinforce the middle portion of the integral corner post with a reinforcing sheet having a portion secured to the body of the sheet at 8 and a portion secured to the outer flange at 9 and a straight portion 10 connecting the portions 8 and 9, as shown in Fig. 3. These reinforcing sheets may comprise a plurality of narrow bands 11, as shown in Figs. 1 and 2, or may comprise a relatively wide sheet 7, as shown in Figs. 4 and 5.

I prefer to extend the reinforcing sheet or sheets beyond the outer flange 5 of the plate and secure them to the longitudinal girders or other frame members of the car, thus tying the end wall to these girders and furthermore tying the girders together.

In the opinion of some engineers it may be objectionable to have the diagonal portion 10 of the reinforcing sheet 7 spaced away from the integral corner post, as such a construction would permit moisture or snow to get behind the reinforcing sheet, therefore, in Fig. 5 I have shown a construction wherein the end portions 15 are extended and formed to fit into the contour of the integral corner post, thus closing one (or both) of the ends of the reinforcing plate. I prefer to secure these extended ends to the web 4 by rivets 16 and inner flange 6 by rivets 17, respectively, of the Z shape corner post to secure unity of action therebetween under stress.

A great many car ends are now in service comprising an upper and lower metallic plate secured together along horizontal lines and having integral horizontal corrugations in each sheet and such sheets are secured along their vertical edges to the corner posts of the car which extend continuously from sill to plate of the car. When an integral corner post is formed in such a construction (as shown in Fig. 4) a weak place is formed where the two plates are secured together because the riveted connection is not as strong as other portions of the integral corner post, therefore, when the end wall comprises two metallic plates secured together along horizontal lines and form an integral corner post I prefer to so position the reinforcing sheet that it spans the juncture of the sheets and is secured to both of said sheets and the width of such reinforcing sheet could be extended to develop the strength of the integral corner post according to known methods of calculating columns and beams. When such sheets are provided with horizontal integral corrugations or embossments I prefer to terminate them into the plate adjacent the reinforcing sheet, as shown at 20 in Fig. 4.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car; the combination of oppositely disposed framing elements, a metallic wall plate having an integral Z-shaped member formed at one margin thereof having each end secured to one of said frame members, said member comprising a web, an inner flange and an outer flange, and a reinforcing sheet having a portion secured to the body part of said plate, a portion secured to the outer flange and a straight portion connecting said portions.

2. In a railway car; the combination of oppositely disposed framing elements, a metallic wall plate having an integral Z-shaped member formed at one margin thereof having each end secured to one of said frame members, said member comprising a web, an inner flange and an outer flange, and a reinforcing sheet having a portion secured to the body part of said plate, a portion secured to the outer flange and a straight portion connecting said portions, said last mentioned portion being secured to a longitudinal frame member of the car.

3. In a railway car; the combination of oppositely disposed framing elements, a metallic wall plate having an integral Z-shaped member formed at one margin thereof having each end secured to one of said frame

members, said member comprising a web, an inner flange and an outer flange, and a reinforcing sheet having a portion secured to the body part of said plate, a portion secured to the outer flange and a straight portion connecting said portions, said reinforcing sheet having extended ends which fit into the Z-shaped member.

4. In a railway car; the combination of oppositely disposed framing elements, a metallic wall plate having an integral Z-shaped member formed at one margin thereof having each end secured to one of said frame members, said member comprising a web, an inner flange and an outer flange, and a reinforcing sheet having a portion secured to the body part of said plate, a portion secured to the outer flange and a straight portion connecting said portions, said reinforcing sheet having extended ends which fit into the Z-shaped member and are secured thereto.

5. In a railway car; the combination of oppositely disposed framing elements, a metallic wall plate comprising two metallic plates secured together along a horizontal line having an integral Z-shaped member formed at one margin thereof having each end secured to one of said frame members, said member comprising a web, an inner flange and an outer flange, and a reinforcing sheet having a portion secured to the body part of both of said plates, a portion secured to the outer flange of both of said plates, and a straight portion connecting said portions.

6. In a railway car; the combination of oppositely disposed framing elements, a metallic wall plate comprising two metallic plates secured together along a horizontal line having an integral Z-shaped member formed at one margin thereof having each end secured to one of said frame members, said member comprising a web, an inner flange and an outer flange and a reinforcing sheet having a portion secured to the body part of both of said plates, a portion secured to the outer flange of both of said plates and a straight portion connecting said portions, each of said plates formed with integral corrugations which terminate into the plate adjacent said sheet.

GARTH G. GILPIN.
